US0D1090383S

(12) **United States Design Patent** (10) **Patent No.:** **US D1,090,383 S**
(45) **Date of Patent:** **** Aug. 26, 2025**

(54) **VEHICLE HOOD**

(71) Applicant: **GM GLOBAL TECHNOLOGY OPERATIONS LLC**, Detroit, MI (US)

(72) Inventor: **Hu Lei**, Shanghai (CN)

(73) Assignee: **GM GLOBAL TECHNOLOGY OPERATIONS LLC**, Detroit, MI (US)

(**) Term: **15 Years**

(21) Appl. No.: **29/919,595**

(22) Filed: **Dec. 5, 2023**

(51) LOC (15) Cl. **12-08**

(52) U.S. Cl.

USPC **D12/173**

(58) **Field of Classification Search**

USPC D12/173, 86, 90, 91, 164, 169; D21/424,

D21/433, 495, 533

Primary Examiner — Garth Rademaker
Assistant Examiner — Kristy N. Nilsson

(57) **CLAIM**

The ornamental design for a vehicle hood, as shown and described.

DESCRIPTION

FIG. 1 is a front and left side perspective view of a vehicle hood showing my new design;

FIG. 2 is a front elevation view of the vehicle hood of FIG. 1;

FIG. 3 is a left side elevation view thereof;

FIG. 4 is a right side elevation view thereof;

FIG. 5 is a back elevation view thereof;

FIG. 6 is a top plan view thereof; and,

FIG. 7 is a bottom plan view thereof.

The broken lines in the drawings depict portions of the vehicle hood that form no part of the claimed design.

1 Claim, 7 Drawing Sheets
